DESIGN FOR A LIQUID DISPENSER OR SIMILAR ARTICLE

Thomas L. Titus, Denver, Colo., assignor to The Wyott Manufacturing Company, Cheyenne,
Wyo., a corporation of Wyoming

Application December 30, 1938, Serial No. 82,065

Term of patent 14 years

To all whom it may concern:

Be it known that I, Thomas L. Titus, a citizen of the United States, residing at Denver, in the city and county of Denver and State of Colorado, have invented a new, original, and ornamental
Design for a Liquid Dispenser or Similar Article, of which the following is a specification, reference being had to the accompanying drawing, forming part thereof.

showing my design.

Figure 2 is a front elevation of the same.

I claim:

The ornamental design for a liquid dispenser or similar article, as shown.

THOMAS L. TITUS.
